UNITED STATES PATENT OFFICE.

ALEXANDER FREDERICK JENKINS, OF BALTIMORE, MARYLAND.

PORTABLE OXYACETYLENE WELDING GENERATOR.

1,410,316.

Specification of Letters Patent. Patented Mar. 21, 1922.

Application filed May 18, 1918. Serial No. 235,430.

To all whom it may concern:

Be it known that I, ALEXANDER F. JENKINS, a citizen of the United States, and a resident of Baltimore, State of Maryland, 5 have invented certain new and useful Improvements in Portable Oxyacetylene Welding Generators, of which the following is a specification.

This invention relates to acetylene generators of the portable type especially adapted for oxy-acetylene welding service, and the invention has for its general object the provision of novel means for initially establishing a suitable gas pressure in the tank above 10 the water level, and to enable the water level to be re-established from time to time.

A more specific object of the invention is the provision of a gas-tight water tank in which the generating unit is submerged, in 15 combination with a hand pump between the gas service pipe and the top of the tank, whereby acetylene gas can be supplied to the space in the tank above the water level for establishing the pressure suitable for oxy-acetylene welding service, so that air will 20 be entirely absent from the tank, and hence no explosive mixture is capable of being produced.

Still another object of the invention is to 25 provide a water connection with the pump whereby the water level in the tank can be re-established from time to time by the manipulation of the pump, there being valves between the pump and the gas service pipe 30 and the water pipe, whereby the pump can be used for pumping either gas or water into the tank as needed.

With such and other objects in view, the invention comprises various novel features 40 of construction and arrangement of parts which will be set forth with particularity in the following description and claims appended hereto.

In the accompanying drawing,

45 The figure is a central vertical section of the acetylene generator.

Referring to the drawing, 1 designates a tank for holding water 2, and in which is 50 submerged a generating unit A of any approved construction which has suitable means (not shown) for holding carbide; and connected with the top of the unit is an outlet pipe 3 which extends up to the top of the tank and then turns downwardly into a vertical portion 4 which telescopes over a 55 vertical pipe 5 fastened to the bottom 6 of

the tank and leading into a washer 7. Leading out of the washer 7 and fastened rigidly to the tank 1 is a service pipe 8. All of the foregoing parts are of common construction, 60 and ordinarily the tank in this type of generator is open at the top, but to render the same suitable for generating gas at pressure adapted for oxy-acetylene work, the top of the tank is sealed by a cover 9 which is provided with a suitable safety valve 10 set for ten or fifteen pounds pressure; and also on the cover 9 is a pressure gage 11.

The top of the tank, or the space above the water level, is filled with acetylene gas, 70 and to supply this gas a pump B is connected with the service pipe 8 through a cock 12 and with the top of the tank by a pipe connection 13. When the tank is supplied with water, the unit A inserted, and the cover 75 closed, the water will attack the carbide in the unit A and gas will flow to the pump as soon as the cock 12 is opened. The pump is then operated so as to force gas into the top of the tank, and when the desired pressure is reached the pumping operation is stopped.

As the generator continues in operation for some time the water level lowers, and it may be desirable to reestablish the water 85 level, and for this purpose the pump B has a water connection 14 controlled by a cock 15. Before the water is pumped into the tank the cock 12 of the gas line is closed 90 and the cock 15 opened, and then, by operating the pump, water is forced into the tank.

The tank is provided with a level indicator in the form of a float 16 which surrounds a tube 17 sealed in and depending from the 95 cover 9, the float being provided with a cage 18 which carries a level-indicating rod 19 that extends upwardly through the tube 17 and has an indicator 20 at the top. The tube 17 is closed by a cap 21, which, when 100 removed, permits the water level to be ascertained by the position of the indicator 20.

On the side of the tank is a sealed outlet 22 of any approved construction, which allows water to run out until the normal water 105 level is obtained.

From the foregoing description taken in connection with the accompanying drawing, the advantages of the construction and method of operation will be readily understood by those skilled in the art to which the invention appertains, and while I have 110

described the principle of operation, together with the apparatus which I now consider to be the best embodiment thereof, I desire to have it understood that the apparatus shown is merely illustrative and that such changes may be made when desired as fall within the scope of the appended claims.

Having thus described my invention, I claim as new and desire to secure by Letters 10 Patent:

1. In a gas generator of the class described, in combination, a tank having inlet and outlet apertures, a generating unit in said tank for generating gas to pass through said outlet aperture, and pump means for returning under pressure to said tank through said inlet aperture a portion of the gas escaping through said outlet aperture.

2. In a gas generator of the class described, 20 in combination, a tank having inlet and outlet apertures, a generating unit in said tank for generating gas to pass through said outlet aperture, and means for creating pressure in said tank including a manually operable pumping device for returning under pressure through said inlet aperture a part 25 of the gas escaping through said outlet aperture.

3. In a gas generator of the class described, 30 in combination, a tank having inlet and outlet apertures, a generating unit in said tank for generating gas to pass through said outlet aperture, and means for forcing into said tank through said inlet aperture a part of the gas escaping through said outlet aperture, or for forcing water into said tank.

4. In a gas generator of the class described, 40 in combination, a tank having a gas outlet, a gas generating unit in said tank for generating gas to escape through said outlet, a gas conduit for leading the gas from the generating unit to the gas outlet, and means for pumping a part of the gas generated in said generating unit into the space around 45 the generating unit.

5. The combination of a water and gas-tight chamber, a gas-generating means therein, a gas service pipe connected with the

said means, and means connected with the service pipe and with the interior of the 50 chamber for establishing in the latter a gas pressure above that derived from said generating means by pumping gas from the service pipe into the chamber.

6. An acetylene generator comprising a 55 gas and water-tight tank, acetylene gas generating means submerged in the tank, a gas service pipe connected with the said means, a pump connected with the top of the tank, a valve-controlled connection between the 60 pump and the service pipe for permitting acetylene gas to be forced into the top of the tank, and a valve-controlled water pipe connected with the pump for permitting water to be supplied to the tank. 65

7. An acetylene generator comprising a gas and water-tight tank, acetylene gas generating means submerged in the tank, a gas service pipe connected with the said means, a pump connected with the top of the tank, 70 a valve-controlled connection between the pump and the service pipe, for permitting acetylene gas to be forced into the top of the tank, a valve-controlled water pipe connected with the pump for permitting water 75 to be supplied to the tank, and a gas-sealed water level indicator connected with the top of the tank.

8. An acetylene generator comprising a gas and water-tight tank, acetylene gas generating means submerged in the tank, a gas service pipe connected with the said means, a pump connected with the top of the tank, a valve-controlled connection between the 80 pump and the service pipe for permitting acetylene gas to be forced into the top of the tank, a valve-controlled water pipe connected with the pump for permitting water to be supplied to the tank, a gas-sealed water level indicator connected with the top of the tank, 85 and a sealed outlet connected with the tank 90 at the normal level thereof. 90

ALEXANDER FREDERICK JENKINS.
